PERCUSSION DRILL

Evin L. Cook, Dallas, Tex., assignor to Socony Mobil Oil Company, Inc., a corporation of New York
Filed July 31, 1959, Ser. No. 830,778
13 Claims. (Cl. 175—92)

This invention relates to drilling devices and relates more particularly to fluid-actuated percussion-type drilling devices.

Rotary-type drilling devices have long been extensively employed in the drilling of oil wells. To a much lesser extent percussion-type drilling devices have been used in well drilling. Some percussion devices have been combined with rotary devices to provide improved means for drilling in particularly hard rock formations.

Drilling devices which utilize the principle of percussive action were first suggested many years ago. Through the years devices have been proposed which achieve percussive action in numerous different ways. Among the suggested ways of obtaining percussive action in drilling have been devices which employ the "water hammer effect obtained by a sudden interruption of the flow of a fluid. One of the early drilling tools which was proposed to operate by the water hammer effect is disclosed in U.S. Patent No. 699,273 issued to W. Wolski on May 6, 1902. In recent years there have been few developments relating to this type of drilling apparatus.

In those instances where percussion type drilling devices have been combined with rotary drilling devices, the water hammer effect has been obtained by sudden interruption of the flow of drilling fluids, often called drilling muds, which are normally used to cool the bit, flush cuttings from the well, and maintain a hydrostatic pressure on the fluids and gases in the formation surrounding the well. This sudden interruption of fluid flow referred to above has generally been a complete stoppage of all fluid flow. Sudden and complete stoppage of the flow of a drilling fluid results in at least two effects which may be detrimental. First, it causes the transmission of shock waves up the drill string with a resultant loss of energy and also mechanical vibration which can be damaging to drilling equipment, such as, pumps, the rotary table, etc., used on the surface. Second, complete interruption of drilling fluid flow may reduce the effectiveness of the flushing action of the fluid.

In the past, the problem of protection of equipment from the effects of a water hammer has been recognized and to some extent shock has been minimized by the use of an enlarged section in the drill string between the bit and the pumps. This enlarged section has been proposed both to control the frequency of the impacts caused by the water hammer and also to provide a cushion to absorb some of the impact to prevent its reaching the pumps and other equipment used. In none of the known liquid driven percussion-type devices which employ the water hammer effect to drive the bit has there been any means for providing continuous flushing of cuttings or permitting continued rotary drilling in event of failure of the percussion device. Failures of the percussion devices by way of valves sticking or otherwise showing faulty operation have required complete shutting down of the drilling operation.

Some of the more recently developed percussion type drilling devices have employed massive hammers which in part are actuated by drilling fluid. The present invention achieves its driving force not from the mass of a hammer device but rather from the mass and velocity of a column of drilling fluid.

Several advantages inherent in the present invention are as follows. Transmission of mechanical vibration to surface drilling equipment is minimized. The mass of

2

a column of drilling fluid provides the driving force for the percussive cutting action of the device. Though conventional rotary bits may be used with the device, it is also possible to use solid head chisel type bits which are not subject to such weaknesses of the rotary bit as bearing failures. The device of the present invention also permits continuous drilling fluid flushing action since it is never necessary that the entire flow of drilling fluid be stopped to obtain percussive action of the bit.

It is an object of the present invention to provide a fluid-actuated percussion-type drilling apparatus which may be employed in conjunction with rotary type drilling apparatus. It is another object of the invention to provide a percussion-type drilling apparatus in which it is not necessary to completely interrupt the flow of all drilling fluid passing through the bit. It is another object of the invention to provide percussion drilling apparatus which minimizes the transmission of shock waves up the drill string to surface equipment. It is another object of the invention to provide percussion drilling apparatus which permits continuous flushing of cuttings from the well. It is a further object of the invention to provide combination rotary and percussion drilling apparatus which will permit continued rotary drilling when valve failures occur in the percussion drilling apparatus. It is another object of the invention to provide a drilling device which may be used with a variety of types of bits. These and additional objects of the invention will be evident from a reading of the following specification and drawings.

Referring to the drawings:

FIG. 1 is a longitudinal cross-sectional view illustrating one form of percussion drilling apparatus constructed in accordance with the invention;

FIG. 2 is a cross-sectional view taken along the line 2—2 of FIG. 1;

FIG. 3 is a view in cross section taken along the line 3—3 of FIG. 1;

FIG. 4 is a cross-sectional view taken along the line 4—4 of FIG. 1;

FIG. 5 is a view in cross section taken along the line 5—5 of FIG. 1; and

FIG. 6 is a longitudinal, cross-sectional view of the lower portion of a modified form of the percussion drilling apparatus shown in FIG. 1.

Referring to FIGS. 1—5, outer tube 10 is a special section of pipe or drill collar secured to the lower end of a drill string, not shown, and is adapted to support percussion drilling apparatus which is operable simultaneously with rotary drilling. The drill string to which tube 10 is secured extends from a rotary table at the surface and functions to rotate the percussion apparatus and convey drilling fluid to it. At its lower end, tube 10 is provided with a plurality of internal longitudinal keyways 12 in the form of slots which are cut into the inside surface of the tube and extend into the tube a predetermined distance from the end of the tube. Threaded onto the lower end of tube 10 is a tubular closure member 13 which has the same inner and outer diameters as tube 10. Closure member 13 provides a shoulder 13a at the lower ends of each of keyways 12.

Positioned within the lower portion of tube 10 is a tubular-shaped valve body and connecting member 20 which is provided at its upper end with a portion of reduced diameter 21. The upper end of portion 21 of body 20 is provided with a longitudinal valve chamber 22 which is cylindrical in form, is closed at its lower end, and is open at its upper end. The longitudinal axis of valve chamber 22 is positioned coincident with the longitudinal axis of body member 20. Portion 21 of member 20 is provided with a plurality of radial flow passages 23 which slope downwardly and outwardly from chamber 22 and serve

to provide fluid communication through the wall of the chamber from a position intermediate the ends of the chamber. A valve 24 is positioned within chamber 22 to provide a moveable closure for the upper open end of the chamber. The stem of valve 24 extends through chamber 22, terminating near the lower closed end of the chamber and is connected to a spring 25 which is secured in the lower closed portion of the chamber and serves to urge the valve upwardly into an open position. Portion 21 of member 20 is provided with a small tubular passage-way 26 which extends into the bottom of chamber 22 to permit fluid to flow into and out of the chamber as the valve stem changes position in the chamber. This is desirable to control the effect of the fluid upon valve action with changes in valve position. The diameter of passage 26 may be varied in order to obtain the desired modulated valve action.

Body member 20 is provided with an axial flow passage 30 which connects with a plurality of radially-positioned flow passages 31 which slope downwardly and inwardly to connect with the upper end of flow passage 30. It is not necessary that the exact configuration of passages 30 and 31 be adhered to so long as their function is provided by passage means through member 20 to permit constant fluid flow from tube 10 through member 20 into the bit. Formed along the outer surface of body member 20 are a plurality of external splines or longitudinal keys 40 which are equal in number to keyways 12 and so positioned that they will mesh with keyways 12 to permit body member 20 to be rotated by tube 10. Keyways 12 are longer than keys 40 in order that body member 20 may slide longitudinally within tube 10. Upward movement of body member 20 is limited by the upper ends of keyways 12, while downward movement of body member 20 is limited by member 13 which forms the closure for the lower ends of keyways 12. In cross section, keys 40 and keyways 12 are so sized that there is a slip fit between them which will permit this longitudinal movement.

Bit adapter 50 is threaded into the lower end of member 20 and is provided with a flow passage 51 which registers with flow passage 30 in member 20. Adapter 50 is provided with a shoulder 52 which abuts against the lower end of member 13 when tube 10 is urged in a downward direction. Threaded into the lower end of bit adapter 50 is a drill bit 55 which is provided with a central flow passage 56 and a plurality of radial flow passages 57. Bit adapter 50 functions to secure the bit to the drilling apparatus and to conduct drilling fluid from passage 30 in member 20 into the flow passages 56 and 57 of the bit.

Positioned within tube 10 and secured to and supported by member 20 is an inner tube 60. The lower end of tube 60 is secured to the upper end of portion 21 of member 20 by means of threads or any other suitable connecting means. The longitudinal axis of inner tube 60 lies coincident with the longitudinal axis of tube 10. The length of tube 60 is determined by considerations which include the frequency of impacts desired to be obtained by the percussion apparatus, as will be explained hereinafter. The internal bore of tube 60 provides a central fluid flow passage 61, while the external surface of tube 60 and the internal surface of tube 10 define an annular fluid flow passage 62. A plurality of guides 70 and 71 are rigidly secured around the outside of inner tube 60 to maintain the tube in its proper position within tube 10. Guides 70 and 71 are not secured to the inner surface of tube 10 but rather are of such length that there will be a slip fit between the guides and the inner surface of tube 10 to permit longitudinal motion of tube 60 relative to tube 10. The particular placement of the guides and the number of guides employed are dependent upon the length and rigidity of tube 60. It is necessary to use only the number of guides required to permit the maintenance of tube 60 in its proper position. As may be observed in FIG. 2, the size of the guides should be such that they will provide a minimum amount of interference with the desired fluid flow through annulus 62.

It will be recognized from the above description that the assembly comprising inner tube 60, body member 20 with its associated valve 24, bit adapter 50, and bit 55 form a unit which is free to move longitudinally within defined limits in tube 10 and is rotated with and by tube 10.

Referring to FIG. 6, the percussion drilling apparatus illustrated differs from the embodiment shown in FIG. 1 in the provision of a bit adapter 80 which is of substantial length. Due to the substantial length of bit adapter 80, it is necessary that it be constructed such that its resonant frequency is equal to the frequency of the impacts delivered by the percussion apparatus with which it is employed. For example, bit adapter 80 may be as long as 100 feet or more. It will readily be recognized that such a lengthy member will have such a large mass and consequently a resonant frequency which must be correlated with the frequency at which the tool is to function in order to prevent the bit adapter from vibrating at cross purposes or in opposition to the impact forces developed by the tool. In other words, if the resonant frequency of such a massive element is not correlated with the frequency for which the tool is designed, the bit adapter may start vibrating out of unison with the tool impact frequency and thus not effectively transmit the impacts from the tool to the bit. The bit adapter may be designed in accordance with the following formula:

$$f = \frac{2c}{l}$$

where:
 f =the frequency at which the tool is designed to operate,
 c =the velocity of sound in the material from which the bit adapter is constructed, and
 l =the length of the bit adapter.

Operation of the percussion drilling apparatus is effected by employment of drilling fluid normally used in rotary drilling to produce percussive action concurrent with rotary drilling action. Drilling fluid is pumped downwardly through the drill string into tube 10 until it arrives at the upper end of inner tube 60 at which point the drilling fluid is divided by tube 60 into two streams of flow. One stream of flow passes within tube 60 through central passage 61, while the other stream of drilling fluid passes downwardly through annular flow passage 62. The stream of fluid flowing through passage 61 passes around valve 24 which is being held in an open position by spring 25, through chamber 22, and outwardly from the chamber through passages 23 into annulus 62 where it rejoins the fluid flowing in annulus 62. The combined streams of drilling fluid then flow into body 20 through passages 31, through passages 30 and 51, into and outwardly from the bit into contact with the formation being drilled.

When the stream of drilling fluid flowing through passage 61 and tube 60 reaches sufficient velocity, the force holding valve 24 open is exceeded, causing the valve to abruptly close. The force holding the valve open and which must be exceeded to effect valve closure is expressed in the formula:

$$F = KX \quad (1)$$

where:

K =the spring constant; and
 X =the distance which the spring must be displaced to effect valve closure.

The forces operating on the valve at the instant before closure are represented by the following formula:

$$F = KX = \Delta P_v A \quad (1a)$$

where:

K =the spring constant;
 X =the distance which the spring must be displaced to effect valve closure;
 ΔP_v =the pressure loss through the valve opening; and
 A =the effective area of the valve.

It will be recognized from the above formula and the definitions of its terms that prior to valve closure the force holding the valve open is that which is being exerted by the spring. This force is, of course, that which must be overcome in order for the flowing fluid to effect closure of the valve. It can thus be seen that at the moment immediately prior to the liquid forcing the valve closed the force being exerted by the pressure drop across the valve as represented by $\Delta P_v A$ will be equal to the force KX which is holding the valve open. At the moment that $\Delta P_v A$ exceeds the force holding the valve open, the valve will abruptly close.

The period of operation of the valve mechanism itself, that is, the time required for the valve to move from open to closed position and vice versa, is controlled by the weight and design of valve used, the spring member, and other considerations such as the viscosity of the fluid. The natural frequency of the valve mechanism should be equal to or greater than the frequency of the impacts to be delivered by the percussion drilling apparatus in order that the natural or resonant frequency of the valve will not interfere with the timing of the impacts of the percussion drilling apparatus. In other words, for satisfactory valve operation the valve should be of such design that it can complete its movements in less time than the period between impacts which is established by the length of inner tube 60. A formula which may be employed in the design of the valve mechanism is as follows:

$$f = \frac{C}{4l} = \sqrt{\frac{Kg}{4\pi^2 W}} \quad (1b)$$

where:

f =the frequency in cycles per second at which the tool is to operate;

C =the velocity of sound in the drilling fluid employed to actuate the tool;

l =the length of the central flow passage 61 within inner tube 60;

K =the spring constant of spring 25;

g =the gravitational constant; and

W =the weight of valve 24 and spring 25.

The abrupt closure of the valve creates a water hammer effect, which is an abrupt pressure build-up, that acts as a driving force on bit 55 effected by downward displacement of the assembly comprising inner tube 60, body 20, and adapter 50. The magnitude of the force exerted on the bit is expressed in the formula:

$$F = \frac{A\rho c \Delta V}{g} \quad (2)$$

where:

F =the force exerted on the bit;

A =the cross-sectional area of passage 61 in tube 60;

ρ =the density of the drilling fluid employed;

c =the velocity of sound characteristic of the drilling fluid in such equipment;

ΔV =the change in velocity of the drilling fluid flowing through tube 60 (equals original velocity, as the fluid velocity goes from original to zero upon complete valve closure); and

g =gravitational constant.

The frequency of the interruption of the flow of the drilling fluids or, in other words, the frequency of the impacts delivered by the bit, is in accordance with the formula:

$$f = \frac{c}{4l} \quad (3)$$

where:

f =the frequency in cycles per second;

c =the velocity of sound in the drilling fluid; and

l =the length of the central flow passage 61 within inner tube 60.

Since the frequency and the length of the flow passage 61 are interdependent variables, it will be readily recognized that the frequency desired may be obtained by constructing the tube 60 with the length necessary to satisfy the above formula. Though the frequency of the impacts delivered by the percussion device is not dependent upon the valve 24 employed or the period of operation of the valve, it is necessary, as has been previously pointed out, that due consideration be given this frequency in designing the valve in order that the period of operation of the valve will be greater than the frequency so that the valve may go through its complete cycle of operation between impacts.

Upon closure of valve 24, the sudden stoppage of flow within passage 61 initiates a compression wave in the drilling fluid at the valve. Simultaneously with the initiation of the compression wave at the valve, a rarefaction wave is formed in the drilling fluid immediately below the valve. The compression wave travels upwardly in passage 61, while the rarefaction wave moves through chamber 22 and passages 23 into annulus 62 where it travels both upwardly and downwardly within the annulus. The portion of the rarefaction wave moving downwardly in the annulus passes through passages 31, 30, and 51 through the bit to produce a lower pressure upon the formation being drilled. The impact caused by the compression wave at valve 24 acts through body member 20 and adapter 50 to force the bit into the formation at substantially the same time that the rarefaction wave reaches the formation. The reduced pressure created by the rarefaction wave improves the cutting action of the bit.

The compression wave moving upwardly in passage 61 and that portion of the rarefaction wave moving upwardly in annulus 62 both arrive at the top of tube 60 at approximately the same time. Since the cross-sectional area of the interior of tube 10 is larger than either passage 61 or annulus 62, the area within tube 10 above tube 60 will, in accordance with well-known principles of fluid mechanics, act as a reflector for both the compression wave in passage 61 and the rarefaction wave in annulus 62. At the top of tube 60 a part of the compression wave moving upwardly in passage 61 is substantially reflected, that is, the reflected compression wave becomes a rarefaction wave which passes downwardly through passage 61 to valve 24. At the same time, the rarefaction wave in annulus 62 is partially reflected at the top of tube 60, that is, the reflected rarefaction wave becomes a compression wave and passes downwardly through the annulus and into chamber 22 through passage 23. The reflected waves arrive at the zone around valve 24 at substantially the same time. The top of the valve is under the influence of a rarefaction wave and the bottom of the valve is under the influence of a compression wave, causing the valve, with the assistance of spring 25, to move to a full, open position. With the valve open, the fluid within passage 61 again accelerates to the velocity necessary to close the valve and thus repeat the cycle.

As it has been stated that the compression wave created upon closure of the valve moves upwardly in passage 61 and is partially reflected at the top of tube 60, it will be recognized that the interface at the end of the tube acts as a reflector and thus a portion of this compression wave not reflected will tend to move upwardly through tube 10 to the equipment on the surface. Similarly, the interface at the end of tube 60 acts as a reflector to rarefaction waves rising through the annulus 62. The term "interface" as used herein means a widening in the path of movement of the waves, compression and rarefaction, which results in a reflection or change in character of the waves. For example, a compression wave arriving at the top of tube 60 spreads out into tube 10 and begins diminishing and changing into a rarefaction wave. The simultaneous arrival of a rarefaction

wave at the top of tube 60 within annulus 62 will tend to reduce and possibly cancel the portion of the compression wave which is being transmitted upwardly within tube 60. By employment of recognized principles of fluid mechanics it is possible to adjust the internal diameters of tubes 10 and 60 such that the relationship between the cross-sectional areas of passage 61 and annulus 62 will be so related that the compression wave moving upwardly in passage 61 will be completely canceled by the rarefaction wave moving upwardly in annulus 62 with the result that no shock is transmitted up to the surface equipment. The provision of an inner tube 60 of sufficient size to deliver a maximum impulse to the bit is, however, not necessarily compatible with the complete elimination of transmission of shock upwardly through tube 10 to the surface equipment. While increases in the force of the impact deliverable by the apparatus are directly related to increases in the cross-sectional area of passage 61, decreases in the amount of shock delivered upwardly through tube 10 are related to minimizing the cross-sectional area of passage 61 relative to the cross-sectional area of annulus 62. It is desirable, therefore, in order to obtain a maximum impact upon the bit that the apparatus be designed with tube sizes which will permit transmission of shock upwardly through tube 10 within limits which may be tolerated by the surface equipment.

As has been previously stated, percussion drilling apparatus constructed in accordance with the invention permits continuous flow of drilling fluids to the formation at the same time that percussive impacts are being delivered to the bit. The drilling fluid flowing through annulus 62 is never completely stopped during the operation of the apparatus. Should the valve 24 become inoperable, rotary drilling may be continued without removing the apparatus from the well bore because of the fact that the flow of drilling fluid continues through annulus 62.

The manner of operation and advantages discussed above are equally applicable to the modified form of the invention disclosed in FIG. 6. While the bit adapter shown in FIG. 1 is sufficiently short in length and low in mass that the frequency of operation of the device is not significant in the design of the adapter, it is necessary to consider such frequency with respect to bit adapter 80. The length of bit adapter 80 should be such that its resonant frequency equals the frequency of the interruptions in the flow of the drilling fluid. The relationships of the factors involved are expressed in the formula:

$$f = \frac{c}{4l} = \frac{c'}{4l'}$$

where:

f = frequency in cycles per second;

c = velocity of sound in the drilling fluid;

l = length of the central flow passage 61 within inner tube 60;

c' = velocity of sound in bit adapter; and

l' = length of bit adapter.

Bit adapter 80 may, as a practical matter, be constructed from one or more lengths of conventional drill collar.

While the invention has been described in the light of certain specific embodiments, it will be recognized that other modifications will occur to those skilled in the art and it is intended that the invention will be limited only within the scope of the appended claims.

I claim:

1. In a fluid-actuated percussion drilling device the combination which comprises an outer tube, an inner tube concentrically positioned within and spaced apart from said outer tube, said inner tube being open at the upper end thereof into said outer tube, a valve at the lower end of said inner tube, spring means on said valve for holding said valve open until fluid flow through said inner tube exceeds a predetermined rate, and body means slidably

secured within said outer tube for supporting said inner tube and valve, said body means being provided with at least one fluid flow passage therethrough in communication with the lower end of said inner tube to permit fluid to flow from said inner tube into said outer tube and at least one fluid flow passage therethrough in communication with said outer tube and extending downwardly through the lower end of said body means, said inner tube, valve, and body means comprising an assembly adapted to reciprocate in response to interruptions effected in fluid flow through said inner tube by action of said valve.

2. In a fluid-actuated percussion drilling device the combination which comprises an outer tube, an inner tube concentrically positioned within and spaced apart from said outer tube, said inner tube being open at the upper end thereof into said outer tube, a valve in the lower end of said inner tube operable in response to fluid flow through said inner tube, spring means on said valve for holding said valve open until fluid flow through said inner tube exceeds a predetermined rate, and body means slidably secured within said outer tube for supporting said inner tube and valve, said body means being provided with passages for directing fluid flow from the lower end of said inner tube into said outer tube and passages for directing fluid flow from said outer tube downwardly through said body means, said inner tube, valve, and body means comprising an assembly adapted to reciprocate in response to interruptions effected in fluid flow through said inner tube by action of said valve.

3. In a fluid-actuated percussion drilling device the combination which comprises an outer tube, an inner tube concentrically positioned within and spaced apart from said outer tube to provide a central fluid flow path and an annular fluid flow path, the upper end of said inner tube being open into said outer tube, body means secured to the lower end of said inner tube, said body means being slidably secured within said outer tube, said body means being provided in the upper portion thereof with a valve chamber opening into said inner tube and fluid flow passages leading from said valve chamber to permit fluid flow from the lower end of said inner tube into said annular flow path, said body means being further provided with a lower central flow passage and a plurality of connecting flow passages to permit fluid flow from said annular flow path downwardly through said body means, a valve supported in said valve chamber at the lower end of said inner tube, and a spring on said valve for holding said valve open until fluid flow through said inner tube exceeds a predetermined rate, said inner tube, valve, and body means comprising an assembly adapted to reciprocate relative to said outer tube in response to interruptions in fluid flow through said inner tube effected by operation of said valve.

4. In a fluid-actuated percussion drilling device the combination which comprises an outer tube provided in the lower portion thereof with a plurality of radially-spaced, internal, longitudinal keyways, a collar threaded to the lower end of said outer tube to provide a closure for the lower ends of said keyways, a body member provided with an upper portion of reduced diameter positioned in the lower portion of said outer tube, said body member being provided with a plurality of longitudinal, external keys spaced to mesh with said keyways in said outer tube, said keys and keyways being so related in cross section that said body member may slide longitudinally in said outer tube while being rotated by said outer tube, said body member being provided with a valve chamber at its upper end and a plurality of radial flow passages extending outwardly from said valve chamber to permit fluid flow downwardly into the upper end of said body member and outwardly into said outer tube, said body member being further provided with a plurality of radial flow passages at the lower end of said portion of reduced diameter, said radial flow passages being

connected at the inward ends thereof with a central flow passage extending downwardly through the lower end of said body member, a bit connecting member secured to the lower end of said body member, said bit connecting member being provided with a shoulder for abutting against said collar to limit upward movement of said body member, an inner tube secured to the upper end of said body member and concentrically positioned within and spaced apart from said outer tube, said inner and outer tubes forming central and annular fluid flow paths, said inner tube being open at the upper end thereof into said outer tube and at the lower end thereof into said valve chamber, means secured around said inner tube for maintaining said inner tube in alignment with said outer tube and permitting said inner tube to move longitudinally relative to said outer tube, a valve supported in said valve chamber at the lower end of said inner tube, and a spring on said valve to hold said valve open until fluid flow through said inner tube exceeds a predetermined rate, said valve being adapted to close in response to a predetermined rate of fluid flow through said inner tube to effect interruptions in said fluid flow, said fluid flow interruptions effecting sudden downward movement of the assembly comprising said inner tube, said body member, said valve, and said bit connecting member.

5. In a fluid-actuated percussion drilling device the combination which comprises an outer tube, an inner tube concentrically positioned within and spaced apart from said outer tube, said inner tube being open at the upper end thereof into said outer tube, a valve at the lower end of said inner tube, said valve having a natural frequency of operation greater than the frequency of impacts deliverable by said device, the distance between said valve and the upper end of said inner tube being in accordance with the formula:

$$l = \frac{c}{4f}$$

where l equals the distance between said valve and the top of said inner tube, c equals the velocity of sound in fluid flowing through said device, and f equals the frequency of impacts deliverable by said device, a spring on said valve to hold said valve open until fluid flow through said inner tube exceeds a predetermined rate, and body means secured to the lower end of said inner tube to support said inner tube and valve and direct fluid flow from said inner tube and said outer tube downwardly, said body means being provided with fluid flow passage means to permit fluid flow from said inner tube around said valve into said outer tube and fluid flow passage means to permit fluid flow from said outer tube downwardly through the lower end of said body means, said body means being slidably secured within and rotatable by said outer tube, said inner tube, valve, and body means comprising an assembly adapted to reciprocate relative to said outer tube in response to interruptions in fluid flow through said inner tube effected by action of said valve.

6. In a fluid-actuated percussion drilling device the combination which comprises an outer tube, an inner tube concentrically positioned within and spaced apart from said outer tube to provide a central fluid flow path and an annular fluid flow path, said inner tube being open at the upper end thereof into said outer tube, body means secured to the lower end of said inner tube, said body means being slidably secured within said outer tube, said body means being provided with a valve chamber at the upper end thereof opening into said inner tube and fluid flow passages leading from said valve chamber to permit fluid flow from the lower end of said inner tube through said valve chamber into said annular flow path, said body means being further provided with a lower central flow passage and a plurality of connecting flow passages to permit fluid flow from said annular flow path downwardly through said body means, a valve sup-

ported in said valve chamber at the lower end of said inner tube, and a spring on said valve to hold said valve open until fluid flow through said inner tube exceeds a predetermined rate, the relation between the frequency of impacts deliverable by said device and the distance between said valve and the upper end of said inner tube being in accordance with the formula:

$$l = \frac{c}{4f}$$

where l equals the distance between said valve and the upper end of said inner tube, c equals the velocity of sound in fluid flowing through said device, and f equals the frequency of impacts deliverable by said device, said inner tube, valve, and body means comprising an assembly adapted to reciprocate relative to said outer tube in response to interruptions in fluid flow through said inner tube effected by operation of said valve.

7. In a fluid-actuated percussion drilling device the combination which comprises an outer tube provided in the lower portion thereof with a plurality of radially-spaced, internal, longitudinal keyways, a collar threaded to the lower end of said outer tube to provide a closure for the lower ends of said keyways, a body member provided with an upper portion of reduced diameter positioned in the lower portion of said outer tube, said body member being provided with a plurality of longitudinal, external keys spaced to mesh with said keyways in said outer tube, said keys and keyways being so related in cross section that said body member may slide longitudinally in said outer tube while being rotated by said outer tube, said body member being provided with a valve chamber at its upper end and a plurality of radial flow passages extending outwardly from said valve chamber to permit fluid flow downwardly into the upper end of said body member and outwardly into said outer tube, said body member being further provided with a plurality of radial flow passages at the lower end of said portion of reduced diameter, said passages being connected at the inward ends thereof with a central flow passage extending downwardly through the lower end of said body member, a bit connecting member secured to the lower end of said body member, said bit connecting member being provided with a shoulder for abutting against said collar to limit upward movement of said body member, an inner tube secured to the upper end of said body member and concentrically positioned within and spaced apart from said outer tube, said inner tube being open at the upper end thereof into said outer tube, said inner and outer tubes forming central and annular fluid flow paths, means secured around said inner tube for maintaining said inner tube in alignment with said outer tube and permitting said inner tube to move longitudinally relative to said outer tube, a valve supported in said valve chamber at the lower end of said inner tube, and a spring on said valve to hold said valve open until fluid flow through said inner tube exceeds a predetermined rate, the relation between the frequency of impacts deliverable by said device and the distance between said valve and the upper end of said inner tube being in accordance with the formula:

$$l = \frac{c}{4f}$$

65
70
75

where l equals the distance between said valve and the upper end of said inner tube, c equals the velocity of sound in fluid flowing through said device, and f equals the frequency of impacts deliverable by said device, said valve being adapted to close in response to a predetermined rate of fluid flow through said inner tube to effect interruptions in said fluid flow, said fluid flow interruptions effecting sudden downward movement of the assembly comprising said inner tube, said body member, said valve, and said bit connecting member.

8. In a fluid-actuated percussion drilling device the

combination which comprises an outer tube, an inner tube concentrically positioned within and spaced apart from said outer tube, said inner tube being open at the upper end thereof into said outer tube, a valve at the lower end of said inner tube, a spring on said valve to hold said valve open until fluid flow through said inner tube exceeds a predetermined rate, body means slidably secured within said outer tube for supporting said inner tube and valve said body means being provided with fluid flow passages for conducting fluid from the lower end of said inner tube around said valve into said outer tube and fluid flow passages for conducting fluids from said outer tube downwardly through the lower end of said body means and an elongated, tubular-shaped bit connecting member secured to the lower end of said body means for securing a bit and conducting fluid flow from said body means to said bit, said bit connecting member having a resonant frequency equivalent to the frequency of impacts deliverable by said device, said inner tube, said body means, said valve, and said bit connecting member comprising an assembly adapted to reciprocate relative to said outer tube in response to interruptions in fluid flow through said inner tube effected by operation of said valve.

9. In a fluid-actuated percussion drilling device the combination which comprises an outer tube, an inner tube concentrically positioned within and spaced apart from said outer tube to provide a central fluid flow path and an annular fluid flow path, said inner tube being open at the upper end thereof into said outer tube, body means secured to the lower end of said inner tube and slidably secured within said outer tube, said body means being provided with a valve chamber at the upper end thereof and fluid flow passages leading from said valve chamber to permit fluid flow from the lower end of said inner tube into said annular flow path, said body means being further provided with a lower central flow passage and a plurality of connecting flow passages to permit fluid flow from said annular flow path downwardly through said body means, a valve supported in said valve chamber at the lower end of said inner tube, a spring secured to said valve for holding said valve open until fluid flow through said inner tube exceeds a predetermined rate, and a tubular-shaped bit connecting member secured to the lower end of said body means for securing a bit to and conducting fluid from said body means to said bit, said bit connecting member having a resonant frequency equivalent to the frequency of impacts deliverable by said device, said inner tube, body means, valve, and bit connecting member comprising an assembly adapted to reciprocate relative to said outer tube in response to interruptions in fluid flow through said inner tube effected by operation of said valve.

10. In a fluid-actuated percussion drilling device the combination which comprises an outer tube provided in the lower portion thereof with a plurality of radially-spaced, internal, longitudinal keyways, a collar threaded to the lower end of said outer tube to provide a closure for the lower ends of said keyways, a body member provided with an upper portion of reduced diameter positioned in the lower portion of said outer tube, said body member being provided with a plurality of longitudinal, external keys spaced to mesh with said keyways in said outer tube, said keys and keyways being so related in cross section that said body member may slide longitudinally in said outer tube while being rotated by said outer tube, said body member being provided with a valve chamber at its upper end and a plurality of radial flow passages extending outwardly from said valve chamber to permit fluid flow downwardly into the upper end of said body member and outwardly into said outer tube, an inner tube concentrically positioned within said outer tube and secured at the lower end thereof to said body member, the upper end of said inner tube being open into said outer tube, a valve secured in said valve chamber to control the

flow of fluid through said inner tube, a spring secured to said valve to hold said valve open until fluid flow through said inner tube exceeds a predetermined rate, said body member being further provided with a plurality of radial flow passages at the lower end of said portion of reduced diameter, said radial flow passages being connected at the inward ends thereof with a central flow passage extending downwardly through the lower end of said body member, and an elongated, tubular-shaped bit connecting member secured to the lower end of said body member for securing a bit and conducting fluid flow from said body member to said bit, said bit connecting member having a resonant frequency equal to the frequency of impacts deliverable by said device.

11. In a fluid-actuated percussion drilling device the combination which comprises an outer tube, an inner tube concentrically positioned within and spaced apart from said outer tube, the upper end of said inner tube being open into said outer tube, a valve at the lower end of said inner tube, a spring on said valve to hold said valve open until fluid flow through said inner tube exceeds a predetermined rate, said valve having a natural frequency of operation greater than the frequency of impacts deliverable by said device, the distance between said valve and the upper end of said inner tube being in accordance with the formula

$$l = \frac{c}{4f}$$

where l equals the distance between said valve and the top of said inner tube, c equals the velocity of sound in fluid flowing through said device, and f equals the frequency of impacts deliverable by said device, a body member secured to the lower end of said inner tube to support said inner tube and valve and direct fluid flow from said inner tube and said outer tube downwardly, said body member being slidably secured within and rotatable by said outer tube, said body member being provided with fluid flow passages for conducting fluid from the lower end of said inner tube through said body member into said outer tube and fluid flow passages for conducting fluids from said outer tube downwardly and outwardly through the lower end of said body member, and an elongated, tubular-shaped bit connecting member secured to the lower end of said body member for securing a bit and conducting fluid flow from said body member to said bit, the length of said bit connecting member being in accordance with the formula:

$$l' = \frac{c'}{4f}$$

where l' equals the length of said bit connecting member, c' equals the velocity of sound in said bit connecting member, and f equals the frequency of impacts deliverable by said device, said inner tube, body member, valve, and bit connecting member comprising an assembly adapted to reciprocate relative to said outer tube in response to interruptions in fluid flow through said inner tube effected by operation of said valve.

12. In a fluid-actuated percussion drilling device the combination which comprises an outer tube, an inner tube concentrically positioned within and spaced apart from said outer tube to provide a central fluid flow path and an annular fluid flow path, the upper end of said inner tube being open into said outer tube, a body member secured to the lower end of said inner tube and slidably secured within said outer tube, said body member being provided with a valve chamber at the upper end thereof and fluid flow passages leading from said valve chamber to permit fluid flow from the lower end of said inner tube into said annular flow path, said body member being further provided with a lower central flow passage and a plurality of connecting flow passages to permit fluid flow from said annular flow path downwardly through said body member, and a valve supported in said valve chamber at the lower end of said inner tube, a spring on said

valve to hold said valve open until fluid flow through said inner tube and valve chamber exceeds a predetermined rate, the distance between said valve and the upper end of said inner tube being in accordance with the formula:

$$l = \frac{c}{4f}$$

where l equals the distance between said valve and the top of said inner tube, c equals the velocity of sound in fluid flowing through said device, and f equals the frequency of impacts deliverable by said device, and a tubular-shaped bit connecting member secured to the lower end of said body member for securing a bit and conducting fluid flow from said body member to a bit, the length of said bit connecting member being in accordance with the formula:

$$l' = \frac{c'}{4f}$$

where l' equals the length of said bit connecting member, c' equals the velocity of sound through said bit connecting member, and f equals the frequency of impacts deliverable by said device, said inner tube, valve, and body means comprising an assembly adapted to reciprocate relative to said outer tube in response to interruption in fluid flow through said inner tube effected by operation of said valve.

13. In a fluid-actuated percussion drilling device the combination which comprises an outer tube provided in the lower portion thereof with a plurality of radially-spaced, internal, longitudinal keyways, a collar threaded to the lower end of said outer tube to provide a closure for the lower ends of said keyways, a body member provided with an upper portion of reduced diameter positioned in the lower portion of said outer tube, said body member being provided with a plurality of longitudinal, external keys spaced to mesh with said keyways in said outer tube, said keys and keyways being so related in cross section that said body member may slide longitudinally in said outer tube while being rotated by said outer tube, said body member being provided with a valve chamber at its upper end and a plurality of radial flow passages extending outwardly from said valve chamber to permit fluid flow downwardly into the upper end of said body member and outwardly into said outer tube, said body member being further provided with a plurality of radial flow passages at the lower end of said portion of reduced diameter, said radial flow passages being connected at the inward ends thereof with a central flow passage extending downwardly through the lower end of said body member, a tubular-shaped bit connecting member secured to the lower end of said body member for securing a bit and conducting fluid flow from said body member to said bit, the

length of said bit connecting member being in accordance with the formula:

$$l' = \frac{c'}{4f}$$

5 where l' equals the length of said bit connecting member, c' equals the velocity of sound through said bit connecting member, and f equals the frequency of impacts deliverable by said device, said bit connecting member being provided with a shoulder for abutting against said collar to limit upward movement of said body member, an inner tube secured to the upper end of said body member and concentrically positioned within and spaced apart from said outer tube, the upper end of said inner tube being open into said outer tube, said inner and outer tubes forming central and annular fluid flow paths through said device, means secured around said inner tube for maintaining said inner tube in alignment within said outer tube and permitting said inner tube to move longitudinally relative to said outer tube, a valve supported in said valve chamber at the lower end of said inner tube, the distance between said valve and the upper end of said inner tube being in accordance with the formula:

$$l = \frac{c}{4f}$$

20 where l equals the distance between said valve and the top of said inner tube, c equals the velocity of sound in fluid flowing through said device, and f equals the frequency of impacts deliverable by said device, and a spring on said 25 valve to hold said valve open and to permit said valve to close in response to a predetermined rate of fluid flow through said inner tube to effect interruptions in said fluid flow, said fluid flow interruptions effecting sudden downward movement of the assembly comprising said inner tube, said body member, said valve, and said bit connecting member.
